US00D849646S

(12) **United States Design Patent** (10) **Patent No.:** **US D849,646 S**
Waldron (45) **Date of Patent:** **** May 28, 2019**

(54) **VEHICLE WHEEL, TOY VEHICLE WHEEL,
AND/OR REPLICAS THEREOF**

(71) Applicant: **Bayerische Motoren Werke
Aktiengesellschaft**, Munich (DE)

(72) Inventor: **Michael Dominic Waldron**, West Hills,
CA (US)

(73) Assignee: **Bayerische Motoren Werke
Aktiengesellschaft**, Munich (DE)

(**) Term: **15 Years**

(21) Appl. No.: **29/632,369**

(22) Filed: **Jan. 8, 2018**

(30) **Foreign Application Priority Data**

Jul. 17, 2017 (DE) 40 2017 100 829

(51) **LOC (11) Cl.** **12-16**

(52) **U.S. Cl.**

USPC **D12/209**

(57) **CLAIM**

The ornamental design for a vehicle wheel, toy vehicle wheel, and/or replicas thereof, as shown and described.

DESCRIPTION

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.

The drawing of FIG. 5 forms no part of the claimed design.

1 Claim, 6 Drawing Sheets
